HYDRAULIC LIFT

Cyrus J. Bristol, Des Moines, Iowa, assignor to
Globe Machinery & Supply Company, Des
Moines, Iowa, a Corporation of Iowa

Application December 15, 1930
Serial No. 502,437

10 Claims. (Cl. 254—93)

This invention pertains to improvements in hydraulic lifts of that type particularly adapted to be used for the purpose of lifting automobiles and the like, and of that type employing a vertical cylinder mounted in the ground and having its upper end substantially level with the ground and employing a lift rod for supporting a suitable head on which tracks are mounted for supporting the automobile, and having hydraulic 5 means for elevating the lift.

This type of lift employs a piston at the lower end of the lift rod, and a leather packing disc. Considerable difficulty has been experienced on account of dirt and water collecting on the outer 15 surface of the lift rod while in its elevated position while the automobile is being washed and cleaned, a portion of the water and dirt being carried downwardly into the cylinder and past the piston, causing the leather packing to be rapidly worn 20 out and destroyed, the water tending to soak the leather and harden the same.

It is, therefore, the object of my invention to provide in connection with the piston employed in hydraulic lifts of the type above described, 25 means whereby the dirt and water will be collected in a suitable trap or container, and in connection therewith means whereby oil escaping past the piston will be collected and returned to the oil chamber.

30 My invention consists in the construction, arrangement and combination of the various parts of the device, whereby the objects contemplated are attained, as hereinafter more fully set forth, pointed out in my claims, and illustrated in the 35 accompanying drawing, in which:

Figure 1 is a side elevation of one type of hydraulic lift, a portion of the cylinder being broken away to show the manner in which my improved piston is mounted therein.

40 Figure 2 is a detail sectional view, taken on the line 2—2 or Figure 1; and

Figure 3 is a detail sectional view, taken on the line 3—3 of Figure 1.

45 Referring to the drawing, I have used the reference numeral 10 to indicate a storage tank or chamber of the usual construction, for the lifting fluid, such as oil, the upper end of the member 10 having an upwardly supported cylinder 11, the top end of which terminates a slight distance above the ground surface and is provided with a bushing 12, said bushing being detachably secured in position by means of bolts 13 and nuts 14. The bushing 12 is preferably formed 50 with a downwardly extending flange 15 project-

ing downwardly into the upper end of the cylinder 10 in the manner clearly illustrated in Figure 3.

Slidably mounted within the cylinder 11 is a piston 16 having an upwardly projecting skirt 17, 60 the periphery of said skirt being provided with a series of annular grooves 18, the central portion of the under surface of the piston head having a boss 19 to which a flexible disc 20 is secured, the edges of said disc being provided with a downwardly and outwardly extending portion 21 to form a packing for the piston and designed to engage the inner surface of the cylinder 11 in the usual manner. A metal disc 22 is mounted adjacent to the under surface of the member 20, 70 and is preferably provided with a downwardly extending flange 23 of smaller diameter than the member 21.

Bolts 24 are provided for clamping the discs 20 and 22 and the boss 19 together. 75

The boss 19 provides an annular space 25 between the disc 20 and the lower surface of the head 16. The head 16 is provided with an opening in which is mounted a vertically arranged overflow pipe 26. 80

Slidably mounted in the bushing 12 is a hollow lift rod 27 having its lower end resting on the piston head 16 and within the skirt 17, in the manner clearly illustrated in Figure 3, the thickness of the skirt 17 being substantially equal to 85 the thickness of the flange 15.

By this construction it will be seen that an annular space 28 is formed between the inner face of the piston 11 and the outer face of the lift 27 above the upper edge of the skirt 17 and below 90 the lower edge of the bushing 12.

Openings 29 are provided in the lift wall, whereby the space 28 is communicated with the interior of the said lift rod, the openings 29 being mounted above the upper edge of the skirt 17 and 95 above the upper end of the overflow pipe 26, the space in the lower end of the lift rod 27 below the upper end of the pipe 26 forming a trap for receiving water and dirt.

In the practical operation it will be seen that 100 if the piston 16 is at its lower limit of movement, with the lifting head 30 resting on the top edge of the bushing 12, and assuming that the hydraulic fluid is forced upwardly in the lower end of the cylinder to engage the lower end of the piston 16, then the said piston will be elevated until the upper edge of the skirt 17 engages the under edges of the flange 15.

As the fluid is applied to the under surface of 110 the piston usually a small amount of the fluid,

which is preferably oil, will be squeezed past the packing 20 and past the outer surface of the skirt 17 into the compartment 28. As the piston reaches its upper limit any oil collected in the compartment 28 will flow through the openings 29 into the trap, and thereby prevent the said oil from being squeezed upwardly between the bushing 15 and the outer surface of the lift rod.

Openings 31 are provided for receiving a suitable pin, which is passed through two of the diametrically opposite openings in the upper edge of the bushing 12 to lock the lift against accidental movement downwardly. The placing of this pin in position usually carries a certain amount of dirt into the interior of the lift rod, a portion of which will be distributed over the outer surface of the said rod and carried inwardly as the said rod is moved downwardly, said dirt collecting in the compartment 28. Oftentimes the automobile is washed while supported in its elevated position, the water collecting on the outer surface of the piston. A portion of this is also drawn into the compartment 28. This water and dirt will be washed into the trap through the openings 29 by the inflowing oil which escapes around the piston, thereby preventing the dirt and oil from being forced downwardly around the outer surface of the piston skirt into engagement with the outer surface of the flange 21, which heretofore has been very troublesome, especially when the upper edge of the skirt 17 is allowed to make engagement with the under surface of the flange 15 in which a tremendous pressure is created and the tendency is to force grit and water downwardly around the outer edge of the skirt.

By providing the openings 29 this pressure is limited, inasmuch as the oil and water will flow freely into the trap by gravity before the piston reaches its upper limit of movement, the lower end of the openings 29 preferably being slightly below the upper edge of the skirt 17.

The annular grooves 18 assist in collecting any water or grit that might otherwise have a tendency to move downwardly past the piston skirt as the same is being elevated. This water and dirt is moved upwardly by oil moving upwardly past the piston skirt.

When the piston has been returned to its lower limit of movement the head 30 rests on the upper edge of the bushing 12 with the piston slightly above the lower ends of the cylinder. Oil at this time is collected into the chamber 10, and any oil within the lower end of the member 27 and above the upper end of the pipe 26 will flow downwardly through the pipe into the recess 25 and past the outer edge of the packing 21, a partial vacuum being created below the piston as the oil in the lower end of the cylinder passes into the chamber 10, causing said surface oil to be sucked past the packing 21. It will readily be seen that any water or dirt will be collected in the lower end of the trap, which may be removed at any time desired through the end of the lift rod.

Thus it will be seen that I have provided a simple, durable and inexpensive piston for hydraulic lifts, whereby water and dirt will be collected and prevented from engaging the leather packing used therewith, and whereby the life of the leather packing will be greatly increased, and whereby oil will be prevented from escaping upwardly through the bushing.

I claim as my invention:

1. A hydraulic lift comprising a vertical cyl-

inder, a piston therein, a hollow lift rod carried by said piston, of smaller diameter than the cylinder, a bushing in the upper end of said cylinder for slidably receiving said lift, said lift having an opening communicating its outer and inner surfaces, said opening being positioned adjacent to the upper edge of the said piston and above the lower end of said lift rod, an overflow pipe mounted in said piston, and a flexible disc adjacent to the lower end of said piston and adjacent to the lower end of said overflow pipe. 80

2. A hydraulic lift comprising a vertically arranged cylinder having a bushing at its upper end, a piston slidably mounted in said cylinder, having an upwardly projecting skirt, the outer surface of said skirt being provided with an annular groove, a hollow lift rod slidably mounted in said bushing and carried by said piston, said rod having an opening communicating its outer and inner surfaces, said opening being above the lower end of said lift rod and substantially even with the upper edge of said skirt, an overflow pipe mounted in said piston, having its upper end slightly below said opening, and means for closing the lower end of said overflow pipe as 100 fluid pressure is applied to the lower end of said piston. 85

3. A hydraulic lift comprising an upright cylinder having a bushing in its upper end, a piston slidably mounted in said cylinder, having an upwardly projecting skirt, a hollow lift rod slidably mounted in said bushing, having its lower end resting within said skirt, said rod having an opening communicating between its outer and inner surfaces, said opening being substantially even with the upper edge of said skirt, an overflow pipe mounted in the piston, having its upper end a slight distance below said opening, and its lower end communicating with the space below the under surface of said piston, and means for automatically closing the lower end of said overflow pipe when pressure is applied to the lower end of said piston. 110

4. A hydraulic lift comprising an upright cylinder having a bushing in its upper end, a hollow lift rod slidably mounted in said bushing and supported on said piston, said lift rod having an opening communicating between the inner and outer surfaces of said lift rod, and above its lower end, to form a chamber for collecting dirt and water clinging to the outer surface of said lift rod, an overflow pipe mounted in the piston, and a flexible disc secured to the lower surface of said piston, having its peripheral edge turned downwardly and outwardly to form a packing flange, said disc being adapted to close the lower end of said overflow pipe as pressure is applied to the lower end of said cylinder. 120

5. A hydraulic lift comprising a cylinder, a piston in said cylinder, a hollow lift rod carried by said piston, having an opening communicating between its outer and inner surfaces, said openings being mounted above the lower end of said lift rod to form a fluid chamber, an overflow pipe mounted in said piston and extending upwardly into said lift rod, whereby fluid collected between the lift rod and the walls of the cylinder will be forced inwardly through said opening in the interior of said lift rod as the piston is moved upwardly, and whereby oil and dirt will be collected in the lower end of said chamber and excess oil will be allowed to flow downwardly through said overflow pipe into the lower end of said cylinder. 135

6. A hydraulic lift comprising a cylinder, a

- piston slidably mounted therein, having an upwardly projecting skirt, annular grooves in the outer surface of said skirt, the central portion of the under surface of the piston having a downwardly extending boss, a flexible disc supported adjacent to the under surface of the said boss and having its peripheral edge turned downwardly and outwardly to form a packing and provide an annular space between said disc and the under surface of said piston, a hollow lift rod carried by said piston, having an opening communicating between its inner and outer surfaces, and an overflow pipe projecting upwardly into the lower end of said lift rod, having its lower end communicating with the annular recess below said piston. 80
7. A hydraulic lift comprising a vertical cylinder having a bushing in its upper end, a piston slidably mounted in said cylinder, having an upwardly projecting skirt, the outer surface of said skirt having annular grooves, a hollow lift rod slidably mounted in said bushing, and supported by said piston, said lift rod having a series of openings, the lower openings being substantially even with the top edge of said skirt for communicating the inner and outer surfaces of said lift rod, the upper openings being designed to receive a pin for limiting the downward movement of said lift rod, said piston being provided with an overflow pipe projecting upwardly into the lower end of said lift rod, and means for closing the lower end of said overflow pipe as pressure is applied to the lower end of said piston. 90
8. A hydraulic lift comprising a vertical cylinder, a piston slidably mounted in said cylinder, a hollow lift rod carried by the upper end of said piston, said hollow lift rod being smaller in diameter than the cylinder to provide an annular space between the lift rod and said cylinder for the collection of water, dirt and similar substances, said hollow rod having an opening connecting its inner and outer surfaces, said opening being above the bottom end of said rod, whereby a chamber will be formed in the lower end of said rod below said opening, an overflow pipe supported in said piston, projecting upwardly into said lift rod with its upper end terminating below said opening, whereby fluid may flow from the annular space around said lift rod through said opening into said chamber, and from said chamber through said overflow pipe to the cylinder, which may be beneath said piston as the piston is moved upwardly, and means for closing the lower end of said overflow pipe when pressure is applied to the lower end of said piston. 95
9. A hydraulic lift comprising a vertical cylinder, a piston slidably mounted in said cylinder, a hollow lift rod carried by said piston, said piston and lift rod having an annular space between the lift rod and said cylinder near the lower end of said lift rod, an opening connecting the inner and outer surfaces of said lift rod, located above said piston, whereby a chamber will be formed below said opening and within said lift rod, an overflow pipe carried by said piston, and means for closing the lower end of said overflow pipe 100 when pressure is applied to the lower end of said piston.
10. A hydraulic lift comprising an upright cylinder, a piston slidably mounted in said cylinder, a hollow lift rod carried by said piston, said hollow lift rod and cylinder being provided with an annular space between the hollow lift rod and the cylinder near the lower end of said lift rod, an opening connecting the inner and outer surfaces of said hollow lift rod, an overflow pipe 110 in said piston having its upper end terminating below said opening, and means for closing the lower end of said overflow pipe when pressure is applied to the lower end of said piston, and permitting it to open as said pressure is released. 115
